RADIO

Stefan A. Unger, Chicago, Ill., assignor to
General Electric Company

Filed Dec. 10, 1969, Ser. No. 20,432

Term of patent 14 years

Int. Cl. D14—03

U.S. Cl. D56—4

FIG.1

FIG.2

FIG.3

FIG. 1 is a front perspective view of a radio in accordance with my design;

FIG. 2 is a right side elevational view; and

FIG. 3 is a top plan view.

The cylindrical upper body of the radio of my design is diagonally shaded to indicate transparency. In addition, the top surface of the radio is stippled to indicate contrast in appearance from the main body of the radio. The design feature of my invention resides in the presence of non-functioning electronic components within the cylindrical upper body of the radio of my design.

I claim:

The ornamental design for a radio, substantially as shown and described.
